VEHICLE DOOR HANDLE SHIELD

Larry D. Heggen, 530 N. 4th, Carlisle, Iowa 50047

Filed Aug. 18, 1969, Ser. No. 18,741

Term of patent 14 years

Int. Cl. D8—09

U.S. Cl. D8—137

Fig. 1

Fig. 2

Fig. 3

Fig. 4

Fig. 5

FIG. 1 is a front elevational view of a vehicle door handle shield showing my new design;

FIG. 2 is a rear elevational view thereof;

FIG. 3 is a side elevational view thereof as viewed from the right of FIG. 1;

FIG. 4 is a side elevational view thereof as viewed from the left side of FIG. 1; and

FIG. 5 is a top view thereof as viewed from above FIG. 1.

I claim:

The ornamental design for a vehicle door handle shield or similar article, substantially as shown and described.
